UNITED STATES PATENT OFFICE.

ALBERT E. SCHNEIDER, OF NEW YORK, N. Y.

ILLUMINATING-SIGN.

1,122,164.

Specification of Letters Patent. Patented Dec. 22, 1914.

Application filed November 1, 1912. Serial No. 729,119.

To all whom it may concern:

Be it known that I, ALBERT E. SCHNEIDER, a citizen of the United States, residing at New York, in the county of New York and State of New York, have invented new and useful Improvements in Illuminating-Signs, of which the following is a specification.

This invention relates to illuminated signs, and has for its object to provide a device of this character in which the lights employed to illuminate it, are concealed within the letters, thereby causing the same to stand out in a clear and distinct manner against a luminous background.

A further object is to provide a device of this character that will be simple in construction and cheap to manufacture and one in which the individual letters are separately wired and connected to spring contacts, whereby the sign can from time to time, be quickly changed without rewiring.

A still further object is to provide the individual letters with separate attaching and adjusting means, whereby they may be adjusted and secured to the most effective position on the base plate.

To these ends the invention consists in the novel details of construction and combination of parts more fully hereinafter described and particularly pointed out in the claims.

Referring to the accompanying drawings forming a part of this specification in which like numerals designate like parts in all the views:—Figure 1 is a front view of my improved sign. Fig. 2 is a cross sectional view thereof with parts of a letter broken away for the sake of clearness. Fig. 3 is a detail perspective view of one of the letters, and Fig. 4 is a sectional view taken on the line 4—4 of Fig. 2.

My improved sign consists of a back frame or base plate 1 provided with an outwardly beveled edge 2 to form a hollow back portion 3. Contact strips 4 and 5 are secured to the front or exposed face of the base plate and are insulated therefrom by means of the strips 6 and 7. These contact strips are adapted to be connected in any suitable manner to electric conducting wires for supplying the sign with electric fluid by which the same is illuminated.

Secured to the base plate 1 by means of the adjusting screws 8, are the characters or

letters 9 which are preferably formed of sheet metal as shown and are suitably coated on their outer or exposed sides with a suitable opaque material. They are mounted with their inner or open sides in a plane parallel with the face of the base plate, are spaced a suitable distance therefrom and have their interior coated with a suitable reflecting material. A series of electric lamps 10 are mounted in the interior of each letter and are electrically connected by the conductors 11 to the spring contacts 12 and 13 which are attached to the letters and which contact with the strips 4 and 5 when the sign is assembled. Any suitable means may be employed for preventing a short circuit of current from one contact to the other.

The exposed surface of the base plate is suitably coated with a white enamel material which contrasts with that on the outer face of the letters and against which is reflected the rays of light from the electric lamps. The mounting of the letters is such that they stand out in bold relief from the sign board and may be easily read when illuminated at night and yet present an artistic and attractive sign by day. From the foregoing it may also be seen that when it is desirous of changing the reading matter of the sign it is necessary only to remove the clamping nuts 14 from the inner ends of the adjusting screws and remove the letter from the base plate, which removal also disconnects, through the spring contacts, the electric light connections, thereby doing away with the necessity of unwiring and rewiring the different letters every time a change of the letters is desired.

It is obvious that those skilled in the art may vary the details of construction and arrangements of parts without departing from the spirit of my invention and therefore I do not wish to be limited to such features except as may be required by the claim.

What is claimed as new is:

A sign comprising a plate, electric conductors mounted upon the plate, letters located in front of the plate and spaced from the same, said letters having front walls parallel with the plate, and side portions at right angles to the plate, lamps mounted upon the front walls of the letters and housed between the side portions thereof,

contacts electrically connecting the lamps with the conductors, and bolts connecting the letters with the plates and bridging the space between the letters and plates and serving as means for holding the contacts against the conductors and supporting the letters in spaced relation from the plate.

In testimony whereof I affix my signature in presence of two witnesses.

ALBERT E. SCHNEIDER.
